SOFT DRINK SHAKER

Filed June 25, 1924

INVENTOR,
Charles G. Sanders,
By Joseph A. Minton
Attorney.

UNITED STATES PATENT OFFICE.

CHARLES G. SANDERS, OF INDIANAPOLIS, INDIANA.

SOFT-DRINK SHAKER.

Application filed June 25, 1924. Serial No. 722,392.

To all whom it may concern:

Be it known that I, CHARLES G. SANDERS, a citizen of the United States, residing at Indianapolis, in the county of Marion and 5 State of Indiana, have invented new and useful Improvements in Soft-Drink Shakers, of which the following is a specification.

My invention relates to an improvement in means for shaking and thereby mixing 10 soft drinks, formerly done by hand, which process when so performed was a time-consuming and laborious job to accomplish the proper results. My soft drink shaker may be set in operation and the drink dispenser 15 occupy himself with other duties during the mixing process. Its rapidly reciprocating motion with the operating mechanism concealed below the counter creates an attractive display as well as being a labor 20 saving device which mixes the drinks much more thoroughly than can be accomplished by hand or by the common mechanical stirrer.

A further object of my invention is to 25 provide means for receiving and securing within the shaker tumblers of varying heights. The drink is served in the tumbler or glass in which it is mixed and consequently different glasses are employed, the 30 heights of which may vary slightly even in the same indicated size of the glasses.

I accomplish these and such other objects as may become apparent in the following description by the means as shown in the accompanying drawing, in which—

Fig. 1 is a front, vertical elevation of 40 my shaker with fragments removed from the shaker head, top strap, and counter top, to show more clearly the height adjusting means, and the means of securing the shaker to the counter; Fig. 2, a side elevation of my shaker, showing the head raised through a quarter of a turn of the shaft, and having fragments of the standard and head rod 45 removed; Fig. 3, a vertical section of the cap taken on the line 3—3 in Fig. 1; and Fig. 4, a top plan view of the head taken on the line 4—4 in Fig. 1.

Like characters of reference indicate like 50 parts throughout the several views.

Referring to the drawing, I form a standard 5 with a horizontal flange 6 adapted to be secured to the underside of a table or counter top 7 by the screws 8 or similar 55 means and having a pilot 9 extending

through and flush with the top side of the top 7. The lower end of the standard 5 is transversely bored through to receive the main shaft 10, on one end of which is rigidly secured a fly-wheel 11 acting also as a 60 drive wheel. The standard has the lower end bifurcated at right angles to the main shaft so as to permit the cam 12 to be received within the standard bifurcation as the shaft 10 is inserted through standard 65 ends, and the shaft 10 is there secured against horizontal displacement by securing the cam 12 to the shaft 10 by placing a pin 13 through a hub 14 of the cam and through the shaft 10. 70

Surrounding the cam 12 is the integral eccentric strap 15 with the extending connecting rod 16 which slidably fits within the bifurcation of the standard 5 and is pivotally connected by a cross pin 17 to the head 75 rod 18 sliding vertically within the central channel 19 bored through the standard 5. It will be noted in referring to Fig. 2, that the connecting rod 16 is attached to the head rod 18 at a distance up from the lower end 80 so as to secure a maximum bearing surface for the head rod 18, and that the head rod 18 has its lower end accordingly bifurcated to straddle the connecting rod 16. 85

The head rod 18 is preferably made hollow and receives in its upper end the lug depending from the head 20 and the head 20 is thereby secured to the head rod 18 by placing a pin transversely through the head rod 18 and the contained lug as shown by 90 dotted lines in Figs. 1 and 2. The head 20 has its upper side cup-shaped to receive the base of a tumbler or glass 21, and to one point on the circumference of the head 20. I attach a cap strap 22 preferably made of 95 spring steel, by forming a vertical slot in the head the width and depth of the strap, inserting a screw 23 through a vertical slot 24 in the strap 22 and entering the screw into the head and drawing the cap strap 22 up in the slot by tightening up the screw 23. The upper end of the cap strap 22 is formed 100 into an eye to receive the pin 25 pivotally securing the cap 26 to the cap strap 22 in the manner of a hinge. 105

Diametrically opposite the cap strap 22, is a similar cap strap 27 secured to the head 20 in the same manner as the strap 22, but having its upper end slightly curved outward and a hole 28 drilled therethrough to 110

permit engagement with the pin 29 projecting from the head 20, forming thereby a means of locking the cap 26 down on the tumbler 21. By springing the strap 27 outward sufficiently, the pin 29 is released and the cap 26 may be swung up and backwardly out of the way so as to permit removal of the tumbler 21.

In order to secure a water-tight joint between the cap 26 and the tumbler 21, I form an annular groove from the inside of the lower rim of the cap to receive a soft rubber gasket 30 which bears directly on the rim of the tumbler and which is compressed as the cap 26 is pressed down to permit the pin 29 to engage in the hole 28 in the strap 27.

Both straps 22 and 27 have inturned lower ends 31 and 32 respectively, against the top sides of which, bear the adjusting screws 33 passing vertically through the head 20 and being adapted to be adjusted from the upper side of the head 20. The cap 26 is suitable spaced apart from the head 20 to the required tumbler height, by loosening the screws 33 and slipping the straps 22 and 27 up or down as required within the limits of the slots 24 and turning the adjusting screws 33 down to contact firmly against the strap ends 31 and 32 so as to prevent any upward displacement of the straps 22 and 27 when the cap 26 is pressed into place over the tumbler, and the side screws 23 are then drawn up tightly.

To operate my device, I employ the common and well known type of fractional horse-power electric motor such as is used in driving a sewing machine, and so mount the motor as to have its drive pulley in rolling contact with the fly wheel 11 and so operate the mechanism of my shaker. However, any other driving means may be employed and the wheel changed to suit the means. The operation of my shaker consists in placing the proper ingredients within the tumbler, as sugar, lemon juice, water and ice for a lemonade drink, placing the tumbler in the head 20, closing the cap 26 over the tumbler, and switching on the motor, whereupon the tumbler will be rapidly reciprocated by means of the reciprocating mechanism as hereinbefore described. The cap 26, being cone shaped within, materially serves to cut, mix, and agitate the ingredients of the drink as is essential for the best results.

Having fully described my invention in the form now best known to me, what I

claim and desire to secure by United States Letters Patent is:

1. In a soft drink shaker, means adapted to give vertical reciprocating motion to a head, adapted to receive a tumbler, a cap on said tumbler, a strap hinged to said cap by its upper end and adjustably engaged by its lower end to said head, a second strap adjustably engaged by its lower end to said head and detachably engaging said cap by its upper end. 70

2. In a soft drink shaker, a head having an upper surface cupped to receive the base of a tumbler and being secured to means adapted to give a vertical reciprocating motion to said head, a conical cap having a soft gasket retained in an annular groove in the base of the cap, said gasket being interposed between the top rim of the tumbler and the cap, a strap hinged by its upper end to one side of said cap and having its lower end formed to contact said head within a vertical slot formed on the side of said head, said strap having a central vertical slot cut through the strap at said contact with the head and said strap having its lower end further depended and thence turned horizontally inward, a second strap elastically and detachably engaging said cap by its upper end and formed to contact near its lower end within a slot formed in the side of said head, said second strap having a central vertical slot cut through the strap at said contact, and said second strap having its lower end further depended and thence turned horizontally inward, horizontal screws passing through the slots in said first and second straps adapted to retain said straps in contact with said head by heads on said screws contacting said straps as said screws are screw threadedly engaged and drawn up in said head, and adjusting screws vertically passing through said head and contacting each of the horizontally inturned ends of said first and second straps. 95 100 105

3. In a soft drink shaker, means adapted to give vertical reciprocating motion to a head, adapted to receive a tumbler, a cap on said tumbler and a plurality of straps engaging said cap by their upper ends and engaging said head by their lower ends, and means of adjustably raising or lowering said straps to vary the distance between said cap and said head. 110 115

Signed at Indianapolis, Indiana, this the 16th day of June, 1924.

CHARLES G. SANDERS.
